(57) CLAIM

The ornamental design for a watchcase, as shown and described.

DESCRIPTION

FIG. 1 is a perspective view of a watchcase showing the new design;

FIG. 2 is a top view of the watchcase shown in FIG. 1;

FIG. 3 is a bottom view of the watchcase shown in FIG. 1;

FIG. 4 is a right side view of the watchcase shown in FIG.

1;

FIG. 5 is a left side view of the watchcase shown in FIG. 1; and,

FIG. 6 is a front view of the watchcase shown in FIG. 1, the rear view being a mirror image thereof.

The broken line showing of a watch face, watch hands, watch band and a crown is for illustrative purposes only and forms no part of the claimed design.

CERTIFICATE OF CORRECTION

PATENT NO. : Des. 491,817 S
DATED : June 22, 2004
INVENTOR(S) : Eric Bonnet

Page 1 of 8

It is certified that error appears in the above-identified patent and that said Letters Patent is hereby corrected as shown below:

On the title page, showing an illustrative figure, should be deleted and substitute therefor the attached title page.

Delete Drawings Sheets 1-6 and substitute therefore the drawings sheets consisting of Drawing Sheets 1-6 as shown on the attached pages.

Signed and Sealed this

Fifteenth Day of March, 2005

JON W. DUDAS
Director of the United States Patent and Trademark Office
